NILS H. ANDERSON, OF EAST HAMPTON, CONNECTICUT, ASSIGNOR OF ONE-HALF TO
WILLIAM A. LORENZ, OF HARTFORD, CONNECTICUT.

TYPE-WRITER PLATEN.

1,235,755.

Specification of Letters Patent.

Patented Aug. 7, 1917.

Application filed August 27, 1914, Serial No. 258,860. Renewed December 30, 1916. Serial No. 139,927.

To all whom it may concern:

Be it known that I, NILS H. ANDERSON, a citizen of the United States, and resident of East Hampton, in the county of Middlesex and State of Connecticut, have invented certain new and useful Improvements in Type-Writer Platens, of which the following is a specification.

This invention refers to typewriter platens and more particularly to what may be termed a noiseless platen.

The purpose of the invention is to provide a platen or roll for typewriting machines and the like that will be light and durable and which by reason of its construction and special formation of parts will produce a platen which when operated upon will throw off less noise than others now in use.

In carrying my invention into effect I employ suitable means for absorbing the sound vibrations caused by the blows of the type upon the platen, in a simple and inexpensive manner, and further include one or more cores or tubes of wood or other suitable material intermediate of which the absorbing material is arranged. The surface of the roll is formed of rubber in the usual manner to form a face against which the type upon the type bars operate.

To enable others to understand my invention I have illustrated the same upon the accompanying drawings forming a part of this specification upon which similar characters of reference will be found to designate like or corresponding parts throughout the several figures and of which

Figure 1 shows a side elevation partially broken away and in section of one of my improved forms of typewriter platens.

Fig. 2 is an end view of the same.

Fig. 3 is a vertical cross section of Fig. 1 and

Fig. 4 is a detached side view partially in section of a slightly modified form of inner tube.

Referring in detail to the characters of reference marked upon the drawings 5 represents a central shaft which may be of the usual or any preferred form and upon which the typewriter platen is mounted and supported to operate within the writing machine carriage, not shown. The platen further consists of an elongated cylindrical

tube 6 which is preferably formed of wood and which is of a uniform thickness and diameter. 7 represents the outer rubber facing or covering that forms the working surface of the platen and against which the paper to be written on is rolled. The special form of inner tube 8 is snugly fitted within the tube 6 and like the said tube 6 is preferably formed of wood. The surface of this tube 8 is turned off in one or more places to form annular pockets 9 between it and the before mentioned wooden tube 6. In Fig. 1 I have shown two of such pockets the same being separated by an annular collar 10 arranged central of the platen. There may, however, be more or less of these pockets, as for instance in Fig. 4 the central collar is omitted thus forming but one long pocket. The end portions of this inner tube are left as of their full diameter in a way to form enlargements or collars 11 thereon, which together with the inner collars if there are any, snugly engage the inner wall of the outer tube 6.

Metal end caps 12 are secured to the before mentioned shaft 5 by means of set screws 13 in a way to support the tubes of the platen upon the shaft. A suitable shock absorbing disk 14 which may be formed of felt or rubber, is arranged between each of these end caps and the ends of the tubes of the platen, so as to further insulate the noise of the type upon the platen, from the shaft. Wood screws 15 which pass through the flanges of the caps engage the end collars 12 of the inner tube in a way to secure the said caps to the platen and form a rigid support for the latter. I also employ rubber washers 16 under the heads of the wood screws and preferably sink the said washers in recesses of the caps so as to allow the heads of the screws to finish flush with the face of the caps and particularly to further insulate the connection of the caps with the rolls.

The pockets 9 before mentioned, formed between the wood rolls, are filled with a suitable shock absorbing material 17 such for instance as paper, felt or the like. This is used in the form of sheets that are wound around the inner roll to fill the pockets and then the said tube is inserted and shoved in place in the outer tube. This material arranged in this way serves to fill the pocket

and absorb the vibrations and materially deaden the noise incident to the striking of the keys upon the surface of the platen.

As will be appreciated the construction thus formed may be manufactured comparatively inexpensively and will produce a platen whose manifold qualities are equal to any if not better than the common form of wood core platen, and as before stated will materially lessen the noise.

Having thus described my invention what I claim and desire to secure by Letters Patent is:—

1. A typewriter platen comprising an inner cylindrical core, an outer cylindrical core, an annular pocket formed between said cores, sound absorbing material in said pocket, a rubber cylinder on the outer core, and heads secured to the ends of the cores.

2. A typewriter platen of the class described, the same consisting of two relatively hard tubular cores one arranged within the other, the inner one of which is formed with a circumferential groove forming a

25 pocket between the two said cores, a sound deadening material filled within the said pocket, a rubber covering upon the outer and hard tube, and end caps secured to one of the said tubes.

3. A typewriter platen of the class described, the same consisting of an inner tubular core having an annular groove there-in forming a pocket, an outer tube of relatively hard material covering the inner tube, a sheet of insulating material wound upon 35 the inner core and within the pocket, a rubber covering upon the outer hard tube, end caps, screws for the attachment of the end caps to the core, and insulating washers between the screws and end caps.

40 Signed at East Hampton in the county of Middlesex and State of Connecticut this 24th day of August A. D. 1914.

NILS H. ANDERSON.
